MORTIS LANGE
BY Morton S. Brockman
ATTORNEY.

UNITED STATES PATENT OFFICE

2,205,295

COLLAPSIBLE CATAFALQUE

Morris Lange, Cleveland Heights, Ohio, assignor
to Superior Funeral Supply Corp.

Application May 24, 1939, Serial No. 275,413

12 Claims. (Cl. 27-1)

This invention relates to biers or catafalques and particularly to the portable folding type used in churches, funeral parlors or private homes and especially for funerals of smaller persons.

5 The primary object of the invention is to provide a catafalque that may be quickly and easily folded.

Another object of the invention is to provide a device of this type that is, when collapsed, self-contained and transportable as a single, compact and lightweight unit.

A further object of the invention is to use the carrying case as a base.

These and other objects and features of the 15 invention will become apparent from a study of the following description and claims together with the accompanying drawing, in which like parts are designated by like reference characters and wherein:

20 Figure 1 is a front view of the collapsible catafalque with parts of the curtain cut away to show the folding framework;

Figure 2 is a side elevation of the folding framework;

25 Figure 3 is an enlarged side elevation of the automatic tilting bracket which supports the top horizontal arms;

Figure 4 is a front elevation of part of the tilting bracket which view is taken along the lines 30 4-4 of the Figure 3; and

Figure 5 is a front view of the framework folded inside of the carrying case base or support.

The collapsible catafalque of this invention consists broadly of a base, primary support member, a secondary support member, horizontal arm members and a draped curtain supported by the aforementioned members.

35 The base member, sometimes referred to herein as the case-base is simply a rectangular trunk-like box 10 provided with a cover 10a. The inside bottom of the case 10 has two pairs of aligned tracks 11 running lengthwise of the case and near to the ends thereof.

The primary support member consists of two 40 pairs of crossed legs 15 pivotally attached together at their centers with the pins 16. Each pair of aligned legs are connected together and spaced with the rods 17, 17a and 17b. There being two such rods 17 below the pivot pins 16 and the two rods 17a and 17b above the pivot pin 16. The bottom ends of the legs 15 are provided with small rollers or pins 18 which move along the tracks 11. The connection between the tracks 11 and the pins 18 being such that they cannot be readily separated.

45 Supported by the crossed legs 15 there is a

horizontal platform 20 which is of a size slightly smaller than the bottom of the case 10. Affixed to the under side of the platform 20, running lengthwise of the platform and adjacent to its four corners, there are two pairs of aligned rails 5 21 which are directly over the tracks 11. The top ends of the crossed legs 15 are provided with small rollers or pins 22 which engage the rails 21 in exactly the same manner as the pins 18 engage the tracks 11. The rear of the platform 10 20 is provided with a vertical back-stop 23 which serves as a stop or guide for the casket to be placed on the platform and also as a brace to strengthen the platform.

The secondary support member also referred 15 to herein as the folding standard consists of a series of crossed levers 25 assembled in the manner of lazy-tongs so that they may be collapsed or extended as desired. The lower pair of crossed levers 25a are a little longer than the others 20 connected thereto and their lower arms are pivotally connected to the pins 22 and are actuated by the legs 15.

The upper pair of crossed levers 25b are a little shorter than the other levers 25 connected thereto. Their short ends are pivotally connected to the short arms 26 so as to form a folding parallelogram in which two obliquely opposite or cross corners are in horizontal and perpendicular positions respectively. The pivot pins 27a and 27b 30 35 which are in perpendicular alignment are a little longer than the other pivot pins 27, in order to accommodate the bracket member hereinafter described.

The horizontal folding arm member consists 35 of a central rod 30 to which there is hingedly attached two side arms 31. The central rod 30 and the side arms 31 are bent or shaped as desired to form the top outline of the draped catafalque, somewhat like the design shown in the Figure 1. The central rod 30 is about as long as the box member 10 and fits therein. The arms 31 fold inward and also fit into the case when so folded. Conventional wing nuts 32 on the hinges, when tightened keep the rod 30 and the arms 31 in a substantially rigid condition.

Because of the fact that the horizontal arm member configuration is normally in a vertical position it is desirable in order to save packing space to fold the arm members flatly or horizontally in the case 10. For this purpose the special tilting bracket illustrated in the Figures 3 and 4 is provided. Furthermore, as it is also desirable to hang the draped curtains 45 a slight distance in front of the folding standard so that when packing and collapsing the device the cur- 50 55

tain 45 is not pinched or cut by the crossed levers 25, 25a and 25b, the special bracket heretofore referred to serves a dual purpose; in that, it also supports the arm member slightly forward of the series of crossed levers 25, 25a and 25b.

The folding bracket consists of an inverted L-shaped rod. The perpendicular portion 35 thereof has a hole 36 which engages the top pivot pin 27a and a little below the hole 26 there is a vertical slot 27 which slidly engages the lower pivot pin 27b.

The horizontal portion 38 of the right angular bent rod projects forward over the platform 20 for a short distance. Connecting the forward end 39 of the projected portion 38 and the sliding pivot pin 27a, there is a folding link or yoke member herein referred to as a truss 41. The top end of the truss 41 is hingedly connected to the end 39 of the horizontal leg 38; the bottom end of the truss 41 is hingedly connected to the pivot pin 27a; and the mid-section of the truss 41 folds on the pin 42, so that when the pin 27a is slid upward in the slot 37, the pin 42 will project forward and the upper end of the truss 41 will tilt 25 from a substantially vertical position to a horizontal position.

The central rod 30 of the horizontal arm member is rigidly mounted on the upper portion of the truss 41 quite close to the forward end 39 of the horizontal leg 38. The Figure 4 clearly shows the alternate positions of the truss 41 and the central rod 30 in broken lines and thus indicates the relative positions of the parts when the device is folded and packed. The movement of the truss 41 and the arm 30 is automatic and depends upon the extension of the support members. Collapsing the supports completely will automatically bring the arm member 30 in a lateral horizontal position while extending the supports 15 and 25 to their limit, will automatically bring the arm member 30 to its vertical position.

The drape or curtain 45 is made of any suitable material which will not crush or wrinkle when creased or folded. The top portion may be shirred and is provided with a means suitable for attachment to the central rod 30 and to the folding arms 31 attached thereto. When mounted on the opened device the curtain hangs a little forward of the secondary support member 25 and completely conceals from front view the top portion of the folding metal framework.

A similar drape or curtain 46 is mounted on the long forward edge and two short sides of the platform 20 so that the front and sides of the primary support member 15 and the case-base 10 are completely concealed from view.

An automatic locking device is provided which retains the metal frame in the open or extended position. This consists of a simple catch element or hooked rod 47 hingedly mounted on the top space rod 17a. This hooked rod 47 has an inverted U-shaped crook 48 at the point where it could engage the adjacent space rod 17b. The rod 47 extends outward almost to the edge of the platform 20 and its extreme end 49 serves as a convenient handle for releasing the crook 48 when it is desired in order to fold the device. When opening the device the crook 48 automatically engages the rod 17 and snaps into engagement therewith.

The advantages of this device over prior art devices may be briefly pointed out in that the device is almost completely automatic in its erection. By simply removing the cover 10a of the

case, lifting the arm member 30 until the catch rod 47 snaps into place and then setting the folding arms 31 with the wing nuts 32, the catafalque is ready for use. By utilizing the individual special carrying case as the base of the structure it may be easily packed and conveniently transported with all of the necessary parts always properly packed so as to eliminate unnecessary wear and tear.

It will now be clear that there is provided by this invention a collapsible catafalque which accomplishes the objects of the invention. While the invention has been described in a special form and while certain general terms and special language have been used, it is to be understood that the embodiment of the invention as described is suggestive only and is not to be considered in a limiting sense. It is to be further understood that there may be other forms or adaptations of the invention and those modifications are also considered to be within the broad scope of the invention as no limitations upon it are intended other than those imposed thereon by the scope of the appended claims.

I claim:

1. A collapsible catafalque comprising in combination, a base member, a primary support member having an extension means thereon receivable by the base member, a secondary support member having an extension means thereon receivable by the base member and connected to the primary member, and curtains mounted on the support members and receivable by the base member, the said support members and curtains being extendable from the said base member.

2. A collapsible catafalque, comprising in combination, a hollow base member, support members having curtains thereon mounted in and receivable by the said base member, and means for folding the support members into the said base member, one of the said support members having an automatically tilting curtain bracket attached thereto.

3. A collapsible catafalque, comprising in combination, a case-base member, a primary support member mounted on the said base member, a secondary support member mounted on the base member, curtains mounted on the said support members, and means including a tilting bracket on the said support members for folding the said members and curtains within the case-base member.

4. In a catafalque, a collapsible frame, comprising in combination, a base member, a primary support member receivable by the base member, a secondary support member actuated by the primary support member, and a folding means on the support members and means in the base member providing for compacting all of the members together.

5. In a catafalque, a collapsible frame, comprising in combination, a case-base member, a platform member, a collapsible stand supporting the platform member on the case-base member, folding arm members, a collapsible standard supporting the folding arm members on the said platform member, the said standard being connected to and actuated by the said stand, and a means on the said supporting members for retaining them in an uncollapsed position.

6. In a catafalque, a collapsible frame, comprising in combination, a case-base member, a stand member mounted on the case-base member and having a platform thereon, a standard member mounted on the stand member and having

cross arms thereon, and a means for simultaneously compacting the said member's platform and arms together.

7. In a catafalque, a collapsible frame, comprising in combination, a case-base member having tracks therein, a collapsible stand member engaging the said tracks and having a platform thereon, the said platform having rails thereon, a collapsible standard member engaging the said rails and having a folding bracket thereon, and a drapery support member mounted on the said folding bracket.

8. In a catafalque, a collapsible frame, comprising in combination, a case-base member, a primary support member mounted in the case-base member, a standard member mounted on the primary support member, an automatically tilting bracket member mounted on the standard member and actuated thereby, and horizontal arms members mounted on the said bracket member.

9. In a catafalque, a collapsible frame, comprising in combination, a case-base member having tracks therein, a stand member having a casket receiving platform thereon, means on the stand member for engaging the said tracks, and a secondary support member mounted on the said stand member, the said stand member and the said support member being simultaneously collapsible into the case-base member.

10. In a catafalque, a collapsible frame, comprising in combination, a base member, a col-

lapsible primary support member mounted on the base member, a standard member mounted on and engaged with the support member, a collapsible and turnable bracket member mounted on and engaged with the standard member, means for simultaneously collapsing the standard member and turning the bracket member, and a cross arm having foldable ends mounted on the bracket member and horizontally turnable upon the collapsing of the support and standard members.

11. A collapsible catafalque, comprising in combination, a base member, a folding primary support member receivable by the base member and connected thereto, the said primary support member having a platform thereon suitable for retaining a casket when in an expanded formation, a folding secondary support member connected to the primary support member and foldable on the said platform when in a contracted formation, and curtains mounted on and concealing the said support members and the base member.

12. In a catafalque of the type having a collapsible standard and curtain supporting arms, a tilting bracket comprising, a rod member attached to the said standard, and a yoke member pivoted on the rod member, attached to the supporting arms, and linked to the said standard in a manner whereby the collapsing of the standard turns the said supporting arms from a vertical to a horizontal position.

MORRIS LANGE.
